UNITED STATES PATENT OFFICE.

JOHN C. SWINDELL, OF ALLEGHENY, PENNSYLVANIA.

GAS-FURNACE.

SPECIFICATION forming part of Letters Patent No. 787,181, dated April 11, 1905.

Application filed April 4, 1904. Serial No. 201,484.

To all whom it may concern:

Be it known that I, JOHN C. SWINDELL, of Allegheny, in the county of Allegheny and State of Pennsylvania, have invented a certain new and useful Improvement in Gas-Furnaces, of which improvement the following is a specification.

My invention relates to furnaces which are heated by gaseous fuel; and its object is to provide means whereby the waste gases evolved from the combustion of the fuel may be utilized in thoroughly and highly heating the air supplied for effecting combustion, such means being of compact and comparatively inexpensive construction and adapted for application in connection with gas-furnaces of various known types without necessitating modification of their essential structural and operative conditions.

The improvement claimed is hereinafter fully set forth.

In the accompanying drawings, Figure 1 is a vertical longitudinal section through a gas-furnace, illustrating an application of my invention, on the line *a-a-a* of Fig. 6; Fig. 2, a similar section on the line *b-b-b* of Fig. 6; Fig. 3, a similar section on the line *c-c* of Fig. 6; Figs. 4 and 5, transverse sections on the lines *d-d* and *e-e*, respectively, of Fig. 3; and Figs. 6 and 7, horizontal sections on the lines *f-f* and *g-g*, respectively, of Fig. 3.

In the instance herein exemplified my invention is shown as applied in connection with a muffle-furnace; but it is not to be understood as being limited to that or any other specific type of furnace.

In the practice of my invention a closed furnace-chamber 1, which is of form and dimensions proper to receive the material to be heated and is constructed of suitable refractory material, is built above a combustion-chamber 2, to which gaseous fuel is supplied from a conduit 3, leading from a gas producer or main and controlled by a valve 4. The gas which is admitted by the opening of the valve 4 passes therefrom into a gas-channel 5, which extends longitudinally beneath the combustion-chamber 2 and communicates therewith by ports 6 in the arched top of the gas-channel. Air for effecting the combustion of the

gas is supplied through channels 7, which are controlled by end doors or valves 7^a and extend longitudinally on opposite sides of the gas-channel 5 and combustion-chamber 2 and communicate with the latter by ports 9 near the tops of its side walls. The channels 7 are divided by horizontal walls 7^b, extending from their inlet ends nearly to their opposite ends, into upper and lower sections, through which the air passes successively in opposite directions. Air is also supplied to the combustion-chamber through channels 10, which extend vertically at opposite sides of the furnace and are curved or arched across its top, said channels communicating with the combustion-chamber on one side thereof by ports 11. The products of combustion or waste gases pass out of the top of the combustion-chamber into channels 12, which surround the top, sides, and bottom of the furnace-chamber 1, from the tops of which channels they pass into the arched upper ends of vertical channels 13 at the sides of the furnace and down the same into horizontal channels 14, which are divided into upper and lower sections by horizontal walls 15, extending from the front of the channels 14 nearly to their ends. The waste gases pass first rearwardly and thence forwardly through said channels and thence into an outlet or discharge flue or channel 16.

The essential and characteristic feature of my present invention consists in the novel combination and relative disposition of the furnace-chamber and the channels by which it is surrounded on its top and sides and which adjoin the combustion-chamber, whereby the incoming air is subjected as thoroughly as practicable to the heat imparted to the walls of the combustion-chamber and of that of the outgoing waste gases or products of combustion and is thereby highly heated prior to its admixture with the gas by the utilization of heat, the most part of which would otherwise be discharged into the atmosphere without useful effect. Referring to the drawings, it will be seen that the lower horizontal air-channels 7 are each interposed between the central combustion-chamber 2 and one of the lateral horizontal waste-gas channels 14. Also each of the vertical air-channels 10 adjoins

one of the vertical waste-gas channels 13, and each of said channels 10, except that at the front of the furnace, is interposed between two of the channels 13. The upper curved 5 portions of the air-channels 10 adjoin and are further heated by the correspondingly-curved upper connection of the waste-gas channels 12. By the employment of suitable valves or dampers controlling the air or the waste 10 channels, or both, in the ordinary manner the incoming air may be subjected to a greater or less degree of heat, as desired. It will thus be seen that provision is made for very complete utilization of the heat of the waste gases, 15 and the relative disposition of the combustion and furnace chambers and the surrounding air and gas channels is such that the entire furnace is of simple construction and is inclosed within substantially rectangular boundaries 20 which do not materially increase the volume required for the furnace and combustion chambers.

I claim as my invention and desire to secure by Letters Patent—

- 25 1. In a gas-furnace, the combination of a furnace - chamber, a subjacent combustion-chamber, a waste-gas channel, one or more, leading out of the combustion-chamber and extending downwardly, a horizontal waste-gas 30 channel located below and communicating with said downwardly-extending channel, a longitudinal partition-wall dividing said horizontal waste-gas channel into sections or compartments which communicate at the end of 35 said channel farther from its discharge, and a horizontal air-supply channel adjoining said horizontal waste-gas channel and commun-

cating by a delivery-port with the combustion-chamber.

2. In a gas-furnace, the combination of a 40 furnace - chamber, a subjacent combustion-chamber, a waste-gas channel, one or more, leading out of the combustion-chamber and extending downwardly, a horizontal waste-gas channel located below and communicating with 45 said downwardly-extending channel, a horizontal air-supply channel interposed between said horizontal waste-gas channel and the combustion-chamber and communicating by a delivery-port with the combustion-chamber, and 50 a longitudinal partition-wall dividing said air-supply channel into sections or compartments which communicate at the end of said channel farther from its supply-opening.

3. In a gas-furnace, the combination of a 55 furnace - chamber, a subjacent combustion-chamber, waste-gas channels, adjoining the bottom, sides, and top of the furnace-chamber, lateral downwardly-extending waste-gas channels communicating with said first-named 60 waste-gas channels, air-supply channels each adjoining one of said last - named waste-gas channels and leading into the combustion-chamber, horizontal waste-gas channels communicating with said last - named waste-gas 65 channels, and air-supply channels interposed between said last-named waste-gas channels and the combustion-chamber, and leading into said combustion-chamber.

JOHN C. SWINDELL.
